JOSEPH ALBERT RONCHETTI, OF WOONSOCKET, RHODE ISLAND, ASSIGNEE, BY MESNE ASSIGNMENTS, TO THE NOISELESS TYPEWRITER COMPANY, OF MIDDLETOWN, CONNECTICUT, A CORPORATION OF CONNECTICUT.

PLATEN-SHIFTING MECHANISM FOR TYPE-WRITERS.

1,103,158.

Specification of Letters Patent. Patented July 14, 1914.

Application filed June 24, 1907. Serial No. 380,601.

To all whom it may concern:

Be it known that I, JOSEPH ALBERT RONCHETTI, residing at Woonsocket, in the county of Providence and State of Rhode Island, have invented certain new and useful Improvements in Platen-Shifting Mechanism for Type-Writers, of which the following is a full, clear, and exact description, such as will enable others skilled in the art to which it appertains to make and use the same.

This invention relates to typewriting machines and is directed more especially to improvements in mechanism employed for shifting the platen for different case printing.

One of the objects of the invention is to provide improved means for shifting the platen to different positions at either side of a normal central position so as to enable the same to receive impressions from any one of three type mounted upon each type bar.

Another object thereof is to provide simple and efficiently operating means for shifting the platen frame such that while the platen is always locked and firmly held in a normal central position, the locking means will in no wise oppose its being readily moved to carry the platen to other printing positions.

Another object is to provide improved means for locking the platen in either of its shifted positions.

A further object is to provide mechanism of the above character which will operate to arrest the shifting movements of the platen or its return movements to normal position substantially without noise.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is illustrated one of the various possible embodiments of my invention, Figure 1 is a

view in vertical section taken through a typewriting machine equipped therewith; Fig. 2 is a vertical sectional view taken substantially on line *a—a*, Fig. 1, looking in a downward direction; Fig. 3 is a similar view on an enlarged scale of a portion of the mechanism shown in Fig. 2; Fig. 4 is a view in rear elevation showing the connections of the shifting mechanism with the platen frame and also the means employed to arrest the shifting movements thereof in predetermined positions; Figs. 5 to 7 inclusive are views showing a different embodiment of the means employed for arresting the platen in the shifted positions and for returning the same to a normal central position; and Fig. 8 is a top plan view of the mechanism shown in Figs. 5, 6 and 7.

Similar reference characters refer to similar parts throughout the several views of the drawings.

In the accompanying drawings, wherein my invention is shown applied to a machine of front strike type, 1 indicates a portion of the framing of the machine, 2 indicates a bed upon which is supported a bank of type bars, one of which is shown at 3, said type bars being adapted to be projected against a common printing point upon the platen 4. The type bars in the present instance are provided with three type characters and are projected to the impression point on the platen by means of toggle mechanism indicated generally at 5, said toggle mechanism being actuated by means of a link, as at 6, which connects the same with the key levers 7, which are held in their raised positions by means of springs, such as shown at 8. The platen 4, in the present instance, is journaled in the upper portion of the platen frame 9 carried in vertical ways formed in the carriage 10, which slides for letter feeding upon a rail 11. Platen frame 9 is provided in its upper portion with a longitudinally extending bar 12 which slides, when the carriage is fed in a block 13, which in turn slides in vertical ways 14 provided upon an upward extension 15 of a tie rod 16 extending longitudinally of the machine 10 and anchored in the front wall thereof as at 17. The rear portion 15 of this tie rod forms

a rigid abutment for the platen and prevents the same from yielding under pressure of the type bars when they are projected thereagainst. The platen frame is provided in its lower portion with a longitudinally extending channel bar 18. The above-described mechanism while forming no essential part of my present invention, is described in order to render my invention 10 clearer of understanding.

Fulcrumed upon a stud 19 extending rearwardly from the lower portion of the framing of the machine, is a lever 20 which extends longitudinally of the machine at the 15 rear portion thereof. This lever, intermediate its ends, carries an arm 21 upon the upper end of which is journaled a roller 22, said roller being located in the channel bar 18 of the platen frame. Arranged upon 20 either side of roller 22, in the present instance, are rollers 23 and 24, said rollers being held in position by means of a leaf spring 25 which conforms to the contour 25 of the upper surface of laterally extending pivots of rollers 23 and 24 and urges them in a downward direction, the spring 25 in its middle portion extending beneath the pivot 26 of roller 22 and urging the same in an upward direction. These three rollers 30 constitute a spring block upon which the channel bar rides when the carriage is fed for letter spacing or on its return movement to begin a new line of writing, the construction of said block being such that no slack 35 can exist in the channel bar inasmuch as the outside rollers are held in engagement with the lower wall of the channel while the intermediate roller is held in contact with the upper wall thereof.

40 Connected to the free end of lever 20, as by means of a universal joint comprising a ball 27 and a socket 28, is a floating lever 29, said floating lever being pivotally attached at 30 intermediate its ends with a 45 shift lever 31 and similarly attached at its forward end at 32 with another shift lever 33. Shift levers 31 and 33, which, in the present instance, are arranged near the left-hand side of the machine, extend transversely therethrough, and are journaled 50 upon a fixed pivot 34 in the rear portion thereof. Shift lever 33 is provided with a dip, as at 35, to accommodate the pivot 30 which connects floating lever 29 with shift lever 31. A clip 36 is adjustably mounted upon floating lever 29 intermediate its point of pivotal connection with the shift levers and held in adjustment thereon by means of a set screw 37, said clip being urged in an 55 upward direction by means of retractile restoring spring 38 attached thereto as at 39 and to a fixed part of the machine. This spring, which, through floating lever 29, urges the shift levers in an upward direction 60

against a fixed cushioned stop 40, operates 65 to restore the platen frame to a normal central position when the same is shifted, as will hereinafter be made more clear. At this point it may be noted that in the present instance stop 40 is so disposed that when the 70 shift levers 31 and 33 are in engagement therewith, the platen through the system of leverage above described will be held in a normal central position which will enable the same to receive impressions from the 75 middle type of the type bars.

Each of the shift levers 31 and 33 in the present instance is provided with forward finger extensions 41 and 42 which are swiveled thereto, as at 43 and 44, said extensions lying in contact with the lateral sides of the inner ends of the shift levers and are provided with notched portions 45 and 46 to receive tongues or projections 47 and 48 formed upon the forward end of the shift 85 levers.

It will be observed by reference to Fig. 1 of the drawings that the notches in the finger extensions are constructed slightly wider than the tongues in order to allow a 90 slight relative movement between the parts of the shift levers, the engagement of the tongues with the walls of the notches serving to limit such movement. Extensions 41 and 42 extend forwardly, then upwardly 95 and at their upper ends are provided with finger keys 49 and 50 respectively. Each of shift levers 31 and 33 has pivoted upon the pivots 43 and 44, which constitute the attaching means for the finger extensions 100 thereto, locking members or detents 51 and 52, which, when the shift levers are in raised positions against fixed stop 40, rest upon a fixed abutment comprised, in the present instance, by a bracket or shoulder 53 extending laterally from the frame of the machine. Thus the shift levers are normally locked in their upward positions by means of detents 51 and 52 and the platen thereby locked in its normal central position. Connected integrally in the present instance with detents 51 and 52 are arms 54 and 55 which extend parallel with finger extensions of the shift levers, said arms at their upper ends being provided with turned over portions or 115 finger keys 56 and 57. Arms 54 and 55 are held in contact with the finger extensions by means of clips 58 and 59, which in the present instance are bent thereabout. Coil springs, one of which is shown at 60, serve to 120 retain detents 51 and 52 upon the shoulders 53. The upper ends of arms 54 and 55, being in engagement with the finger keys of forward extensions 41 and 42 of the shift keys, also operate to hold said finger extensions in their uppermost positions, which positions are determined by the engagement of the tongues 47 and 48 with the upper 125

walls of the notches 45 and 46. By reason of this construction a depression of one of the shift lever keys will cause a slight pivotal movement between the main portion 5 of the shift lever, and the forward extension thereof, such movement causing the detent or locking member carried thereby to ride off the shoulder 53, whereupon the shift lever will be unlocked and further pressure 10 thereon will cause the same to swing to its downward position to shift the platen.

Each of the locking detents, 51 and 52, is provided with forward extension or catch 61, which is adapted, when the shift lever 15 is in a depressed condition, to take under a shoulder 62 which extends upon the frame of the machine, such engagement serving to lock the shift levers in their downward positions and the platen in shifted positions. 20 This operation is effected by the operator concurrently depressing the finger key of one of arms 54 or 55 when the shift key is depressed. When catch 61 is in engagement with shoulder 62 and the shift lever held 25 in a depressed position, a slight pressure on the shift lever will disengage the parts, whereupon one of the springs 60 will retract the locking member and withdraw the catch from the shoulder, thereby allowing a 30 free return of the shift lever to normal position.

Pivoted, as at 63, upon the rear wall of the machine is a link 64 which, at its outer end, is pivotally attached to a similar link 65 35 journaled upon a stud screw 66 upon lever 20 intermediate its ends. A similar link 67 is pivoted in the frame of the machine beneath lever 20 and is similarly connected to stud screw 66 by means of a link 68. These 40 two pairs of connected links constitute a double toggle joint either one of which when straightened out operates noiselessly to limit the up or down stroke of the platen carriage. The toggles are returned to the position 45 shown in Fig. 4, which shows the platen frame in a normal central position by means of a spring 69 which is interposed between the points of pivotal connection of each pair of toggle links.

50 In Figs. 5 to 8 inclusive there is shown a modification of the mechanism for limiting or arresting the upward and downward shifting movements of the platen. This mechanism comprises a U-shaped member 55 70 mounted upon the rear wall of the framework of the machine, said U-shaped member being mounted upon eccentrics 71 so as to be capable of a slight adjustment. Journaled upon lever 20 intermediate its ends is 50 an arm 72 which, at its outer end, carries a roller 73 which takes between parallel arms 74 and 75 of U-shaped member 70. This roller, when lever 20 is raised or lowered, rolls along the upper or lower inner surfaces

of the arms 74 and 75 of member 70, and 65 when the position shown in Figs. 6 and 7 is reached, operates through arm 72 and lever 20 to limit the shifting movement of the platen frame. Arm 72 is urged to the position shown in Fig. 5 by means of a coil 70 spring 76 attached at one end of lever 20 and at its upper end to an arm 77 extending from the pin 78 upon which arm 72 is fixed. This construction also enables the lever 20 to be arrested when swung upwardly or 75 downwardly by the shift levers in a silent manner, inasmuch as the same is arrested without any impact or concussion. Spring 76 also aids in the returning of the platen carriage to its normal central position. 80

Having thus described the construction of my invention, the operation thereof may now be understood. Assuming the parts to be in normal position as shown in Fig. 1 of the drawings, a depression of either of 85 the shift keys 49 or 50 will first, as above described, cause the locking detent carried thereby to ride from its shoulder 53, thereby allowing a free depression of the shift key, the other shift key remaining in locked 90 position and the pivotal connection thereof with floating lever 29 forming a stationary fulcrum upon which said floating lever swings under compulsion of the lever being depressed. The swinging of floating lever 95 29 will cause lever 20 to swing upward or downward in accordance with the particular shift lever depressed and through arm 21 and the roller block cause a corresponding movement of the platen, such movement 100 being, as above described, limited by the straightening of one of the toggles comprised by links 64 and 65 or 67 and 68 or in the embodiment shown in Figs. 5 to 8 inclusive, by the movement of roller 73 along 105 the inner periphery of the arm of U-shaped member 70. When pressure is released upon the shift levers the parts return to normal position through the influence of retractile spring 69 which acts on floating lever 29 intermediate its points of attachment with the shift levers, said operation being assisted in a measure by means of the coil spring 110 69 which serves to fold the toggle or, as shown in Figs. 5 to 8 inclusive by spring 76 115 which operates to return the parts to the position shown in Fig. 5. If the operator desires to retain the platen in a shifted position, it is only necessary to depress the lock key concurrently with the shift key, whereupon the catch 61 of the locking detent will take under the fixed shoulder 62 arranged in front thereof, whereby the platen will be held in a shifted position until a further depression of the depressed shift key will 120 allow spring 60 to disengage the catch from the shoulder. 125

It will accordingly be seen that I have

provided mechanism well adapted to attain, among others, all the objects and aims of my invention in an exceedingly simple and efficient manner. The platen is held immovable in normal position, thus allowing erasures to be made without causing the carriage to be depressed under the pressure necessarily employed in such operations. The platen, moreover, is readily locked in either its raised or lowered position and is returned to its normal central position by means of a single restoring spring which also serves to return both of the shift levers to their raised positions. The means employed to arrest the shifting movements of the carriage in both embodiments herein shown operate without noise, the platen being arrested without any impact or concussion.

20 While I have shown my invention as applied to a front strike machine of the above type, it is obvious that the same may be employed with great facility in many other types of machines although the same is of peculiar value in the type of machine shown herein.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:—

1. In a typewriting machine, in combination, a shiftable platen, a shift lever connected therewith, means for locking said lever in normal position, and means associated with said shift lever for releasing said locking means when it is attempted to depress the lever.

2. In a typewriting machine, the combination with a shiftable platen, of a pair of shift levers, and a lever pivotally connected at different points in its length with each of said shift levers and also connected with the platen, said lever being adapted to swing upon either of said points of connection with the shift levers as a fulcrum when the other of said levers is depressed.

3. In a typewriting machine, in combination, a shiftable platen, a shift lever connected therewith, a locking member positioned beneath said shift lever to automatically

lock the same in raised position, and means connected with said shift lever adapted to unlock said locking member when said shift lever is depressed.

4. In a typewriting machine, the combination with the platen carriage normally held in an intermediate position and adapted to shift to either side of said intermediate position for different case printing, of a pivotally mounted lever, a rod connected with said lever and with the carriage which furnishes an actuating connection between those parts, a pair of shift levers, and a second lever connecting said first lever with each of said shift levers, said shift levers when depressed being adapted to shift the platen to either side of its normal printing position for different case printing.

5. In a typewriting machine, the combination with a shiftable carriage, of means for shifting the carriage from a normal intermediate position to a position at either side thereof for different case printing, comprising a pair of shift levers, a lever connected to each of said shift levers, a second lever pivotally mounted in the rear portion of the machine and having a connection with said first lever, and a rod connected with said second lever and said carriage which furnishes an actuating connection between those parts.

6. In a typewriting machine, the combination with a pair of shift levers normally locked in raised positions, and a shiftable platen normally resting in an intermediate printing position and locked in such position by the shift levers.

7. In a typewriting machine, the combination with a pair of shift levers normally locked in their raised position but adapted to automatically unlock when pressed, and a shiftable platen normally locked in an intermediate printing position by the shift levers adapted to be shifted in opposite directions thereby.

8. In a typewriting machine, in combination, a shift lever, and a shiftable platen connected therewith and locked against upward movement thereby.

9. In a typewriting machine, the combination with a shiftable platen, of a shift lever connected therewith, and means carried by the shift lever for locking it in its raised position whereby the platen is positively held against downward movement to a shifted printing position, said locking means being automatically unlocked when the shift lever is depressed.

10. In a typewriting machine, in combination, a shiftable platen, a pair of shift levers, and means for locking the platen in normal position through said shift levers.

11. In a typewriting machine, the combination with a shiftable platen, and a pair of shift levers connected therewith having

- means jointly to lock the platen in intermediate position and singly to lock the same in a shifted position.
12. In a typewriting machine, in combination, a shiftable platen for upper or lower case printing, a pair of shifting levers for shifting the platen to either side of an intermediate position, a lever pivotally connected to each of said shift levers and having a connection with the platen, and locking means on each shift lever for holding one of said shift levers stationary when the other is depressed, whereby the pivotal connection with the lever connected therewith operates as a stationary fulcrum upon which the latter swings to shift the platen. 70
13. In a typewriting machine, in combination, a platen adapted to be shifted to either side of the normal printing position for upper or lower case printing, a pair of shift levers, a lever pivotally connected to each of said shift levers and having a connection with the platen, and means for holding each of said levers stationary during a depression of the other permitting the pivotal connection of each of said shift levers with said second lever to operate as a stationary fulcrum about which the latter swings to shift the platen. 80
14. In a typewriting machine, in combination, a shiftable platen, a pair of shift levers, and a lever connected to each of said shift levers and also connected with the platen adapted to be swung upon its pivotal connection with one of said shift levers about its connection with the other when either shift lever is depressed, whereby the platen is shifted. 90
15. In a typewriting machine, in combination, a shiftable platen, a shift lever connected therewith, and means for automatically locking the shift lever in its raised position and adapted automatically to unlock when the shift lever is pressed. 100
16. In a typewriting machine, in combination, a shiftable platen, a shift lever carried therewith, and a locking member carried by the shift lever adapted for automatically locking the same in its raised position but adapted to move automatically to an unlocking position when the shift lever is pressed. 110
17. In a typewriting machine, in combination, a shiftable platen, a pair of shift levers connected therewith, and automatically operating means for locking the shift levers in raised position whereby the platen will always be locked in intermediate position, said locking means being adapted automatically to unlock the shift levers when the same are pressed to allow the platen to be shifted. 120
18. In a typewriting machine, in combination, a shiftable platen, a pair of shift levers connected therewith, a locking mem- 130
- ber carried by each of said shift levers adapted automatically to lock the same in a raised position whereby the platen will always be locked in intermediate position, said locking members being adapted to move to an unlocking position when the shift levers are pressed. 75
19. In a typewriting machine, in combination, a shiftable platen, a shift lever connected therewith, and means carried by said shift lever adapted automatically to lock the same in raised position, whereby the platen will be locked in normal position, said locking means being also adapted to lock the shift lever in its depressed position 80 whereby the platen may be locked in its shifted position. 75
20. In a typewriting machine, in combination, a shiftable platen adapted normally to rest in intermediate position, a pair of shift levers each of which is connected therewith and is adapted to shift the same to another printing position, and a locking member carried by each of said shift levers adapted automatically to lock the same in its raised position, whereby the platen will also be locked in its normal position, each of said locking members being adapted automatically to unlock the shift lever upon which the same is carried when said shift lever is pressed. 95
21. In a typewriting machine, in combination, a shiftable platen, a shift lever connected therewith, and a locking member carried by said shift lever adapted to lock the same either in a raised or in a depressed position. 100
22. In a typewriting machine, in combination, a shiftable platen, a pair of shift levers connected with the platen and adapted to shift the same from a normal intermediate position, and a locking member carried by each of the shift levers adapted automatically to lock the same in its raised position and capable of manual manipulation to lock the same in a depressed position. 115
23. In a typewriting machine, the combination with a shiftable platen, of a pair of shift levers connected therewith, and a locking member carried by each of the shift levers adapted to lock the same either in a raised position whereby the platen will be held against movement in normal position, or in a depressed position whereby the platen will be locked in a shifted position. 120
24. In a typewriting machine, in combination, a shiftable platen, a pair of shift levers connected therewith, a locking member carried by each of the shift levers adapted automatically to lock the same in its raised position and capable of manual manipulation to lock the same in a depressed position, and a finger key for actuating said locking member. 125
25. In a typewriting machine, the combi- 130

- nation with a movable part, of means for silently arresting and limiting the movement of said movable part comprising a pair of pivotally connected members, one of 5 which is connected to said movable part and the other to a relatively fixed part of the machine, and means connected to one of said parts adapted to aid in returning said parts to normal position.
- 10 26. In a typewriting machine, the combination with a shiftable platen, of a shift lever connected therewith, and a locking member swiveled upon said shift lever adapted automatically to lock the same in 15 a raised position whereby the platen will be locked in normal position, said locking member being also adapted to lock the shift lever in a depressed position thereby locking the platen in a shifted position.
- 20 27. In a typewriting machine, in combination, a shiftable platen, a shift lever connected therewith, a locking member swiveled upon the shift lever and adapted when the same is in a raised position to engage 25 a shoulder extending from a fixed portion of the machine whereby the shift lever will be locked in its raised position and the platen thereby locked in normal position, said locking member being adapted automatically to become disengaged from said 30 shoulder when the shift lever is depressed, and a finger key connected with said locking member adapted to engage the same beneath a second shoulder extending from a fixed 35 portion of the machine whereby said shift lever may be locked in a depressed position and the platen thereby locked in a shifted position.
28. In a typewriting machine, the combination with a shiftable platen, of a two-part 40 shift lever connected therewith, the parts of said shift lever being capable of a limited relative movement, and a locking member carried by one of said parts adapted normally 45 to hold said shift lever in a raised position, said locking member, owing to a relative movement of the parts of said shift lever when the same is depressed, being adapted automatically to unlock the same, 50 whereby the platen may be shifted.
29. In a typewriting machine, in combination, a shiftable platen, a shift lever connected therewith, said shift lever comprising two members swiveled to each other and 55 capable of a limited relative movement, a locking member carried by said shift lever adapted when the same is in a raised position to rest upon a shoulder extending from a fixed portion of the machine, said locking 60 member, due to the relative movement of the parts of said shift lever, being adapted to ride off said shoulder when the shift lever is depressed to shift the platen.
30. In a typewriting machine, in combination, a shiftable platen, a shift lever con- 65 nected therewith, said shift lever comprising a plurality of parts swiveled together and capable of a limited relative movement, a shoulder extending from a fixed portion of the frame of the machine, a locking member swiveled upon said shift lever and resting upon said shoulder when the shift lever is in a raised position, and means connecting said locking member with one of the parts of said shift lever whereby when said shift lever is depressed a relative movement will take place between the parts thereof, thereby unlocking the shift lever from its locked position and allowing the same to shift the platen.
31. In a typewriting machine, the combination with a shiftable platen, of a shift lever connected therewith, said shift lever having a finger extension journaled thereon and capable of a limited movement relative thereto, a locking member carried by said shift lever, a shoulder extending from a fixed portion of the machine upon which said locking member rests when the shift lever is in a normal position whereby the same is locked in a raised position and the platen thereby locked in normal position, said locking member having a positive connection with the finger extension of said shift lever, whereby when the same is depressed a relative movement will take place between said finger extension and the shift lever, thereby causing said locking member to be disengaged from said shoulder to allow said shift lever to be depressed and the platen thereby shifted.
32. In a typewriting machine, in combination, a shiftable platen, a shift lever connected therewith, and a locking key swiveled upon said shift lever adapted normally to lock the same in a raised position, said locking key when struck during a depression of said shift lever operating to lock the same in a depressed position.
33. In a typewriting machine, in combination, a shiftable platen, a shift lever connected therewith, a locking key swung upon said shift lever adapted normally to lock the same in a raised position, thereby locking the platen in normal position, said locking key being automatically moved from a locking position when the shift lever is struck and when struck concurrently with said shift lever being adapted to lock the same in a depressed position, and fixed means with which said locking key engages.
34. In a typewriting machine, the combination with a shiftable platen normally held in intermediate position and adapted to be shifted in opposite directions therefrom, a lever having a connection with the platen, a second lever having a pivotal connection with said first lever and adapted to swing the same in opposite directions, and movable means operating through a connection

with said first lever adapted to determine the shifted positions of the platen.

35. In a typewriting machine, the combination with a shiftable platen normally held in an intermediate printing position, of a pair of shift levers, of a lever pivotally connected at different points in its length with said shift levers, means for connecting said lever with the platen, said lever being adapted to swing upon each of its points of attachment with said shift levers as a fulcrum to shift the platen to either side of its normal position, and means connected with said lever intermediate its point of attachment 10 with the shift lever adapted to restore the platen to normal position, said means being also adapted to restore the shift levers to normal position.

36. In a typewriting machine, the combination with a shiftable platen normally held in an intermediate printing position, of a pair of shift levers, a lever to which both of said levers are pivotally connected at different points in the length thereof, said lever 20 being connected with the platen, the pivotal connection of one of said levers with one of said shift levers operating as a stationary fulcrum when the other of said shift levers is depressed, and a restoring spring 25 for the platen operating through said lever at a point intermediate the points of attachment thereof with said shift levers.

37. In a typewriting machine, the combination with the traveling carriage, of a platen frame provided with a channel bar 35 mounted therein, a platen carried by said platen frame, means operating through said channel bar for shifting said platen frame to carry the platen to another printing position, and movable means operating through said channel bar adapted to interpose a yielding resistance to a movement of said platen frame, said latter means also operating to limit the shifting movement of the 40 platen.

38. In a typewriting machine, the combination with the carriage, of a platen frame sliding in ways therein, a platen carried by said platen frame, a channel bar carried by 50 the platen frame, means operating through said channel bar adapted to shift the platen from a normal intermediate printing position to a printing position at either side thereof, and movable means operating 55 through said channel bar adapted to determine the shifted positions of the platen.

39. In a typewriting machine, the combination with the carriage, of a platen frame sliding in ways provided therein and adapted 60 to rest in an intermediate printing position, said platen frame being provided with a channel bar and platen carried by said platen frame, a lever pivoted in the rear portion of the machine and extending longitudinally thereof, an arm extended up-

wardly from said lever, a block comprised by a plurality of resiliently connected rollers carried by the upper end of said arm, said block riding in said channel bar, a pair of shift levers connected with said lever 70 adapted to swing the same in opposite directions, whereby the platen will be shifted to either side of its normal printing position, and means operating through said lever adapted to interpose a yielding resistance 75 to the swinging movements thereof, said means being also adapted to determine the shifted positions of the platen.

40. In a typewriting machine, the combination with a carriage provided with ways, of a platen the frame of which is slidably mounted in said ways, a channel bar connected with the platen, a plurality of resiliently connected rollers located in said channel bar, a lever pivotally supported in the rear of the machine and extending longitudinally thereof, an arm connecting said lever with said rollers, a pair of shift levers and a second lever connecting said first lever with each of said shift levers, said shift levers 85 when depressed being adapted to shift the platen to either side of its normal printing position for different case printing.

41. In a typewriting machine, the combination with the carriage having a shiftable platen frame for carrying the platen, of means for shifting the platen from a normal intermediate position, comprising a pair of shift levers, a lever connected to each of said shift levers, a second lever pivotally 90 mounted in the rear portion of the machine having a universal connection with said first lever, and an arm connecting said second lever with the platen frame.

42. In a typewriting machine, the combination with the carriage, of a platen frame slidably mounted in ways therein, said platen frame having a channel bar, a platen carried by said platen frame, and means for shifting the platen to either side of an intermediate printing position for different case printing, comprising a pair of shift levers, a floating lever pivotally connected to each of said shift levers, a lever pivoted upon one end upon a fixed pivot and having a pivotal connection at its opposite end with said floating lever, an arm extending from the second lever, and a block carried by said arm adapted to ride in the channel bar of the platen frame.

43. In a typewriting machine, the combination with the carriage provided with vertically disposed ways, of a platen frame mounted to slide in said ways, a platen carried by said platen frame, said platen frame being provided in its lower portion with a channel bar, means operating through said channel bar to shift the platen frame to carry the platen from a normal intermediate printing position to a printing position at 130.

either side thereof, comprising a pair of shift levers extending transversely of the machine and pivoted in the rear portion thereof, a floating lever pivotally connected with each of said shift levers, a second lever pivoted in the rear portion of the machine and having its opposite end connected with said floating lever, an arm extending upwardly from said second lever, and a plurality of rollers carried by said arm, said rollers riding in said channel bar.

44. In a typewriting machine, the combination with a carriage provided with vertical ways, of a platen frame slidably mounted in said ways, a platen carried by said platen frame having in its lower portion a longitudinally extended channel bar, and means for shifting the platen frame to carry the platen from an intermediate printing position to a printing position at either side thereof, comprising a pair of shift levers extending transversely to the machine and fulcrumed in the rear portion thereof, a floating lever having a pivotal connection with each of said shift levers whereby when one of said levers is depressed the pivotal position of the other shift lever with said lever operates as a fulcrum upon which the latter swings to shift the platen, a second lever fulcrumed at one end in the rear portion of the machine and having its other end connected for universal movement with floating lever, an arm extended upwardly from said second lever, a roller journaled upon said arm and located in said channel bar, a roller located in said channel bar to either side of said first roller and resiliently connected therewith, and a restoring spring for the platen operating through said floating lever at a point intermediate its connections with said shift levers.

45. In a typewriting machine, the combination with the carriage, of a platen frame shiftably mounted therein, a platen carried by said platen frame, means for shifting the platen frame to carry the platen from a normal printing position to another printing position, and movable means connected with the platen and also connected with a fixed portion of the machine adapted to arrest a shifting movement thereof.

46. In a typewriting machine, the combination with the carriage, of a platen frame mounted therein and adapted to be shifted upward and downward from a normal printing position, a platen carried by said platen frame, and means connected with the platen frame and also connected with a fixed portion of the machine adapted to arrest the shifting movements thereof.

47. In a typewriting machine, the combination with the carriage, of a platen frame slidably mounted therein, a platen carried by said platen frame, means for shifting the platen frame to carry the platen from a nor-

mal position to other printing positions, and movable means connected with said platen frame and also with a fixed portion of the machine adapted to determine the shifted position of the platen.

48. In a typewriting machine, the combination with the carriage, of a shiftable platen frame mounted therein, a platen carried thereby, means for raising or depressing the platen frame to carry the platen to a printing position at either side of a normal intermediate position, movable means connected with said platen and also with a fixed portion of the machine adapted to arrest the platen in shifted positions, and means for resiliently opposing the movement of said arresting means.

49. In a typewriting machine, the combination with the carriage having a shiftable platen frame adapted to carry the platen, of means for shifting the platen from a normal intermediate position, comprising a pair of shift levers, a lever connected to each of said shift levers, a second lever having a universal connection with said first lever, an arm extending upwardly from said second lever, said platen frame being provided with a channel bar, and a spring roller block mounted upon said arm located in said channel bar.

50. In a typewriting machine, the combination with the traveling carriage, of a platen frame mounted in ways therein adapted to be raised or depressed to carry the platen to a printing position at either side of a normal intermediate position, means for shifting the platen comprising a pair of shift levers, a lever connected to each of said shift levers, a second lever connected with the platen frame, and a universal connection between said first and second levers.

51. In a typewriting machine, the combination with the traveling carriage, of a platen frame slidably mounted therein, said frame being provided with a longitudinally extending channel bar, of means for shifting the platen frame to carry the platen from normal intermediate position, comprising a pair of shift levers, a lever connected to each of said shift levers, a second lever pivotally mounted in the rear portion of said machine and having a universal connection with said first lever, an arm extended from said second lever, a roller block carried by said arm and located in the channel bar of the platen frame, and means for arresting the platen when shifted to either side of its normal intermediate position operating through said second lever.

52. In a typewriting machine, the combination of shifting mechanism for changing the printing relation of the platen and type, a shift key for the same, and a lock key for the shifting mechanism having a finger-engaging part adjacent to the shift

- key in position to be engaged and moved with the shift key by the same finger that operates the shift key, substantially as set forth.
- 5 53. In a typewriting machine, the combination of shifting mechanism for changing the printing relation of the platen and type, a shift key, and a shift lock key having a finger engaging part arranged in rear 10 of the shift key in a position to permit the shift key to be depressed without touching the lock key or the lock key to be engaged and depressed with the shift key by the tip of the same finger that operates the shift 15 key, said shift lock key being pivotally mounted upon the shift key lever.
54. In a typewriting machine, the combination with a movable part, of means for silently arresting and limiting the movement 20 of said movable part comprising a pair of pivotally connected members, one of which is connected to said movable part and the other to a relatively fixed part of the machine, and spring means connected to one of said pivotal members adapted to aid in returning said parts to normal position.
55. In a typewriting machine, in combination, a platen adapted to be shifted to a different printing position, and shifting mechanism therefor, including key-released 30 locking means, acting when in normal position to directly lock the platen in normal position.

In testimony whereof I affix my signature, in the presence of two witnesses.

JOSEPH ALBERT RONCHETTI.
